THIRD TO SAMUEL SHAPIRO, OF BROOKLYN, NEW YORK.

ELECTRIC FIRE-ALARM

1,080,480.

Specification of Letters Patent.

Patented Dec. 2, 1913.

Application filed December 27, 1912. Serial No. 738,832.

To all whom it may concern:

Be it known that we, FREDERICK RICORDS and MAHLON LEWRY, both citizens of the United States, and residents of the city of New York, borough of Brooklyn, in the county of Kings and State of New York, have invented a new and Improved Electric Fire-Alarm, of which the following is a full, clear, and exact description.

10 Our invention relates to electric fire alarms which may be installed in a building with an indicator on each floor having a bell and a switch, with electrical connections for ringing all the bells and for lighting a certain lamp on each floor when an alarm is given, by closing one of the switches.

15 Still other objects of the invention will appear in the following complete specification, in which the preferred form of our invention is disclosed.

In the drawing, similar characters of reference refer to corresponding parts in all the figures.

25 Figure 1 is a perspective view of one of the indicator boxes with the door open; Fig. 2 is a front elevation of an indicator box; Fig. 3 is a sectional side elevation of an indicator box shown in Fig. 2; and Fig. 4 is 30 a diagrammatic view showing the wiring.

By referring to the drawings, it will be seen that each of the indicator boxes has a rear member 5 with side members 6, a top 7, a bottom 8, the front indicator box being normally closed by a door 9 mounted on the hinges 10. In this indicator box there is a horizontal partition 11 which, with the top of the box 7, forms a compartment 12, there being another horizontal partition 13 which with the bottom 8 of the box forms a compartment 14. These partitions 11 and 13 are connected by a vertical partition 15 which forms the rear of the lamp compartments 16. These lamp compartments are 45 divided by horizontal members 17 and by vertical members 18, so that one of the compartments 16 will be disposed at the rear of each figure or letter, forming indicating means 19 on the door 9. These indicating means 19 are constructed by cutting openings 20 in the door in the form of figures 21 and letters 22, which indicate certain portions of the building. These openings 20 are covered at the inner side of the door 9 55 by glass 23 or some other translucent mem-

ber. As shown in the drawings, there are three vertical columns of these compartments 18 each being the rear of one of the indicating means 19 consisting of a figure 21 and a letter 22. This construction is provided for a four story building, the top row of indicating means 19 referring to the fourth floor, and the left hand indicating means 4^c referring to the west end of the fourth floor, the indicating means 4^c indicating the central portion of the fourth floor, and 4^e indicating the east portion of the fourth floor. In the same way the other indicating means 19 refer to the different floors and proportions thereof, as for instance, the bottom row of the indicating means referring to the first floor, the left hand one 1^w referring to the west portion of the first floor, and 1^c indicating the central portion of the first floor and the right hand one 1^e indicating the east portion of the first floor.

In the compartment 14, at the bottom of each of the indicating boxes, there are three switches 24, each of the indicating boxes being provided with an electric bell. Each building is provided with one of these indicating boxes on each floor so that when an alarm is sounded, a bell will be rung on each floor and a lamp will be lighted indicating where the fire is. The wiring is shown in Fig. 4 of the drawings, in which wires 26 and 27 are the main wires of an electric circuit, and the wires 28 and 29 are the wires of the bell circuits, which are connected electrically with the bells 25^a and 25^b.

In Fig. 4 of the drawing, we have shown the connections for a two story building, but it will be understood that this same wiring arrangement may be used in a building of any size and number of stories. The lower indicator box in the arrangement shown in Fig. 4 of the drawings has the electric bell 25^b and the lamps 30—31—32—33—34 and 35, also the switches 36—37 and 38. The indicator box in the second story is provided with the lamps 39—40—41—42—43 and 44, and with the switches 45—46 and 47. The bell wires 28 and 29 are connected with the bell 25^b by means of the wires 48 and 49, and the bell wires 28 and 29 are connected with the bell 25^b by the bell wires 50 and 51. The switch 38 is connected with the bell wire 28 by means of the wires 52 and 53. The switch 37 is con-

ected with the said bell wire 28 by means of the wires 54 and 55 and the switch 36 is connected with the bell wire 28 by means of the wires 56 and 57. The bell wire 29 is connected with the main wire 27 by means of the wires 58 and 59. The switch 47 is connected with the bell wire 28 by means of the wire 60 and 61. The switch 46 is connected with the bell wire 28 by means of the wires 62 and 63. The switch 45 is connected with the bell wire 28 by means of the wires 64 and 65. The switch 38 is connected with the main wire 26 by means of a wire 66. The switch 37 is connected with the main wire 26 by means of a wire 67. The switch 36 is connected with the main wire 26 by means of a wire 68. The switch 47 is connected with the main wire 26 by means of a wire 69. The switch 46 is connected with the main wire 26 by means of a wire 70. The switch 45 is connected with the main wire 26 by means of a wire 71. The main wire 27 is connected with one set of terminals of the lamps 30-31-32-33-34 and 35 by means of a wire 72. The main wire 27 is connected with one set of terminals of the lamps 39-41-40-42-43 and 44 by means of a wire 73. The switch 38 is connected with the other terminals of the lamps 30 and 39 by means of the wire 52 and the wire 74. The switch 37 is connected with the other terminals of the lamps 31 and 40 by means of the wires 54 and 75. The switch 36 is connected with the other terminals of the lamps 32 and 41 by means of the wire 56 and the wire 76. The switch 47 is connected with the other terminals of the lamps 44 and 35 by means of the wires 60 and 77. The switch 46 is connected with the other terminals of the lamps 43 and 34 by means of the wires 62 and 78. The switch 45 is connected with the other terminals of the lamps 42 and 33 by means of the wires 64 and 79. It will therefore be seen that when the wiring which is shown in Fig. 4 is used in a two story building, and the indicator with the switches 36-37 and 38 is disposed on the first floor and the indicator with the switches 45-46 and 47 is disposed on the second floor, that when the switch 38 is closed which refers to the east portion of the first floor, it will connect the main wires 26 and 27 with the bells 25^b and 25^a by means of the wires 66-52-53-28-48-49-29 and 58, and also by means of the wires 50 and 51. This will ring the bells 25^b and 25^a, one of which is located on the first floor and the other is located on the second floor. This will sound the alarm, and the persons in the building by looking at the indicators not only can tell on which floor the alarm was given, but also can tell whether the fire is at the central portion of the said floor and at which end of said floor. In the diagram shown in Fig. 4 of

the drawings, the switch 38 which is on the first floor, refers to the eastern portion of the first floor, and when the switch is closed, it indicates that the fire is at the eastern portion of the first floor. With the closing of the switch, the main wires 26 and 27 are connected electrically with the lamps 30 and 39 by means of the wires 66-52-74-72 and 73 which will light the lamps 30 and 39 as has been stated. Should the alarm be given on the second floor and the fire be in the central portion of the second floor, the switch 46 will be closed which will ring the bells 25^b and 25^a in the manner indicated, and will also light the lamps 43 and 34 by the circuit extending between the main wires 26 and 27 by the wires 70-62-78-73 and 72. In this way not only is an alarm sounded, but information is furnished to all the persons on every floor of the building, so that they may know where the fire is and what is the safest way to leave the building.

Having thus described our invention, we claim as new and desire to secure by Letters Patent:

1. In a fire alarm, a box, a partition for forming with the wall of the box a compartment, a second partition forming with the opposite wall of the box a second compartment, a third partition extending substantially from the first to the second partition, and having lamp sockets, partitions which with the third partition divide the space on one side of the third partition and between the first and second partitions into a plurality of compartments, electric lamps in the last-mentioned compartments, and seated in the lamp sockets, a face member in the box, covering the last-mentioned compartments, and having translucent portions, indicating predetermined locations, switches in one of the first two-mentioned compartments, a bell, two main wires in the box on the other side of the third partition, wires extending from one of the main wires to the switches, wires on the last named side of the third partition connecting each of the switches with a terminal of one of the lamps, wires connecting the other terminals of the lamps with the other main wire, two bell wires on the last named side of the third partition, wires connecting the bell wires with the bell, wires connecting one of the bell wires with the switches, and a wire connecting the other bell wire with the last-mentioned main wire.

2. In a fire alarm, a box, a partition forming with the wall of the box a compartment, a second partition forming with an opposite wall of the box a second compartment, a partition extending substantially from the first to the second partition, and having lamp sockets, partitions which with the third partition divide the space on one side of the third partition and between the first and second partitions into a plurality of com-

partments, electric lamps in the last-mentioned compartments, the electric lamps being seated in said lamp sockets, a face member for the box covering the last-mentioned compartments and having translucent portions indicating predetermined locations, switches in one of the first-two-mentioned compartments, a bell, two main wires in the box on the other side of the third partition, 10 two bell wires in the box on the last named side of the third partition and connected with the bell, and wires connecting the main wires with the switches, the lamps and the bell wires, the last-mentioned wires extending to the first - two- mentioned compartments, where they may be readily connected and disconnected.

2. In a fire alarm, a box, a partition forming with a wall of the box a compartment, 20 a second partition forming with another wall of the box a second compartment, a third partition connected with the first and second partitions intermediate of their front and rear edges, and having lamp sockets, 25 partitions which divide the space in front

of the third partition into a plurality of compartments, electric lamps, in the last-mentioned compartments, the electric lamps being seated in said lamp sockets, a face member for the box covering the last-mentioned compartments and having translucent portions indicating predetermined locations, switches in one of the first-two-mentioned compartments, a bell, two main wires in the box in the rear of the third partition, 30 two bell wires in the box in the rear of the third partition, and connected with the bell, and wires connecting the main wires with the switches, the lamps and the bell wires, the third-mentioned wires extending to the first- 40 two-mentioned compartments, whereby they may be readily connected and disconnected.

In testimony whereof we have signed our names to this specification in the presence of two subscribing witnesses.
